UNITED STATES PATENT OFFICE.

JANE M. JOHNSON, OF CHICAGO, ILLINOIS.

COMBINATION CORSET AND DETACHABLE ABDOMINAL SUPPORT.

1,242,946.

Specification of Letters Patent.

Patented Oct. 16, 1917.

Application filed December 22, 1916. Serial No. 138,325.

To all whom it may concern:

Be it known that I, JANE M. JOHNSON, a citizen of the United States, and a resident of the city of Chicago, in the county of 5 Cook and State of Illinois, have invented certain new and useful Improvements in Combination Corsets and Detachable Abdominal Supports; and I do hereby declare that the following is a full, clear, and exact 10 description of the same, reference being had to the accompanying drawings, and to the numerals of reference marked thereon, which form a part of this specification.

This invention relates to an improved construction wherein an abdominal support is 15 associated with a corset, and may be easily attached, detached or adjusted with respect to the corset, and when used acts to hold the abdominal organs thrust upwardly and 20 inwardly in their normal position.

It is an object therefore of this invention to construct a combination corset and abdominal pad which is adjustably as well as 25 releasably associated with the corset, permitting the corset to be worn in the usual manner and overcoming the discomfort due to the use of a separate abdominal support.

It is also an object of this invention to provide in combination with a corset having 30 attaching tabs, an abdominal support adapted to be adjustably connected to the tabs to be worn with the corset.

It is furthermore an object of this invention to construct a combination corset and 35 abdominal support, the latter constructed to receive a removable filling which gives the desired shape and contour to the support, and with the support adjustably connected to the corset.

40 It is finally an object of this invention to construct an improved abdominal support adapted to be worn in conjunction with and attached to a corset.

The invention (in a preferred form) is 45 illustrated in the drawings and hereinafter more fully described.

On the drawings.

Figure 1 is a view showing the device embodying the principles of my invention during the process of attachment thereof upon 50 a person.

Fig. 2 is a fragmentary central vertical section taken through the corset on the person with parts shown in elevation.

55 Fig. 3 is a detail section taken on line 3-3 of Fig. 2, with parts omitted.

Fig. 4 is a fragmentary enlarged detail, showing the attachment of the abdominal pad to the corset.

Fig. 5 is a similar view of a slightly modified form of abdominal pad.

Fig. 6 is a sectional detail on line 6-6 of Fig. 4.

Fig. 7 is a view similar to Fig. 6, of a slightly modified construction. 65

Fig. 8 is a sectional detail taken on line 8-8 of Fig. 5.

Fig. 9 is an edge view of one section of the abdominal pads detached from the 70 corset.

Fig. 10 is a sectional detail taken on line 10-10 of Fig. 7, with parts omitted.

Fig. 11 is an enlarged detail view taken on line 11-11 of Fig. 4.

Fig. 12 is an enlarged detail section taken 75 on line 12-12 of Fig. 4.

Fig. 13 is a view similar to Fig. 8, illustrating a slightly modified construction.

As shown on the drawings:

The corset consists of two sections denoted 80 respectively by the reference numeral 1, which may be integral with one another or joined by suitable lacing, as desired at the back. Said sections are adapted to fasten to one another along the front of the person 85 when worn either by hooks or lacing or in any other suitable and well known manner, the details of which are not entered into here. Said respective corset sections 1, on the interior surface are provided with eye- 90 let tabs 2 and 3, respectively, stitched substantially in a vertical position at the lower abdominal portion of the corset. The abdominal pad illustrated in Figs. 1 to 4, inclusive, consists of two sections 4 and 5, 95 respectively, which are attached to the corset tabs 2 and 3, by lacing 6, whereby the pad sections are held in place and are adjustable or may be from the corset if desired.

The pad section 4 is provided with a series 100 of eyelets 7, along one edge and the pad section 5, is provided with a series of hooks 8, whereby said pads may be connected to one another upon the person as shown in Fig. 1, prior to the attachment of the respective corset sections to one another.

As shown in Fig. 6, said pad sections 4 and 5, are provided with a filling of hair or other material 9, and the pad section 5, on its inner surface is provided with a flap 110 10, which serves to span the gap between the pad sections at their point of connection by

the hooks and eyes 7 and 8, along the line of contact with the body.

In the modified form of device illustrated in Fig. 7, I have illustrated the filling of the pad sections 4 and 5, as comprising removable pads 11, filled with hair or other material. In this form of construction, the pad members 4 and 5, may be preferably constructed of chamois with suitable openings to receive the filler members 11, inserted thereinto, and the latter may be preferably constructed of oiled silk with the filling therein, so that by removing the pad members 11, the pad sections 4 and 5, may be washed.

In the form of structure illustrated in Figs. 5 and 8, I have shown an abdominal pad 12, provided with a filling material 13, and at one side provided with a tab 14, adapted to be laced to the eyelet tab 3, of the corset. At its other side said pad 12, is provided with hooks 15, releasably engaged through a series of eyes upon a tab 16, which is in turn laced to the corset tab 2.

Figs. 11 and 12, are illustrative of the manner in which the main pad and filler pad of the different structures shown are stitched together, but although a particular form is shown, this is only for purpose of illustration, and it is obvious that any other construction can be used without departing from the principles of my invention.

Fig. 13 illustrates a novel adaptation of the form of pad shown in Figs. 5 and 8, wherein the filling 13, of the pad 12, is omitted, and in its place a removable insert of wood, aluminum or other material 17, is provided, constructed and placed within the pad according to the particular function which the insert is designed to perform. It is obvious that although the filling material or filler pads shown in the various structures herein disclosed are of a certain shape

and curvature, as for instance that shown in detail section in Fig. 10, any form or shape of pad may be used, and any number of insert pads provided and that the same may be disposed in any desired position, according to the purpose for which used.

I am aware that various details of construction may be varied through a wide range without departing from the principles of this invention, and I therefore do not purpose limiting the patent granted otherwise than necessitated by the prior art.

I claim as my invention:

1. The combination with a corset and eyelet tabs connected thereto, of a pad laced to said tabs adapted to receive different fillings therein.

2. The combination with a corset of tabs secured thereto, pad sections secured to the tabs and means detachably connecting the pad sections, said pads adapted to receive different shaped filling members.

3. The combination with a corset of tabs secured thereto, a plurality of pads laced along their outer ends to the tabs each of substantially wedge shape having the thick ends abutting and means detachably connecting the abutting ends of the pads together.

4. The combination with a corset of a tab secured to each section of the corset, a complementary pad detachably connected to each tab tapering in thickness from the outer edge to the inner edge and hooks and eyes for detachably connecting the pads along the inner edges.

In testimony whereof I have hereunto subscribed my name in the presence of two subscribing witnesses.

JANE M. JOHNSON.
